FIG. 3.

FIG. 1.

FIG. 4.

FIG. 2.

Albert Henry Crollly
INVENTOR:

By his ATTORNEY.

UNITED STATES PATENT OFFICE.

ALBERT HENRY CROLLY, OF AUCKLAND, NEW ZEALAND.

MOP.

Application filed January 2, 1925. Serial No. 66.

To all whom it may concern:

Be it known that I, ALBERT HENRY CROLLY, citizen of the British Empire, residing at 39 Crummer Road, Ponsonby, in the city of Auckland, Dominion of New Zealand, have invented new and useful Improvements in Mops, of which the following is a specification.

This invention relates to mops for house-
hold use and the like of the type which comprises a body portion provided with a handle, cotton or other material suitable for a mop being secured to said body portion. The invention has for its object the provision of a simplified and cheap mop of the type described which is light and effective and more easily worked and handled than the heavier type.

The object of the invention is effected by the provision of improved means for securing the mopping material to the body portion of the mop comprising a specially designed band preferably having its edges curved showing a substantially U shape in cross section and designed to avoid wear on the mopping material and for strength said band being preferably secured by means such as nails to the underneath edge of said body portion, so as to secure the mopping material between the metal band and the underneath edge of said body portion.

The body portion is provided with a handle of convenient length of the usual kind secured thereto in any suitable manner.

In the accompanying drawings illustrating the invention Figure 1 is a perspective view of the securing band, Figure 2 is a perspective sectional elevation of the mop, Figure 3 is a section of the mop, Figure 4 is a view of the means for securing the band and mop material to the mop body. The body 1 of the device is made preferably of

wood and preferably circular in plan and has a hole 7 bored in its to take a usual handle in it secured as usual by means of a nail 45 or screw passing through hole 8 in the body. A preferably metal band 2 preferably circular in plan has rounded or curved edges so as to prevent injury to the mop material 4 and to form a channel 3 to receive snugly the 50 heads 6 of nails 5. These nails 5 are used to secure material 4 made preferably of cotton of convenient length for use which is passed over the rounded edges of the band 2 preferably equal lengths being on each side 55 of the band. This band 2 is placed evenly round the underneath edge of the body 1 and is securely fastened thereto by means of the nails 5 which are driven home on the body 1.

A special advantage attained by this invention is that the securing of the mop material to the body portion can be cheaply and rapidly done as follows:

The band carrying the mop material arranged on it as described is placed over a 65 hollow holder see Figure 4 in the wall of which are vertical holes wherein the nails are inserted head down. The head and band being firmly held by suitable means a lever is operated to thrust up rods which push 70 up all the nails home simultaneously through the band into the body thus securing the band and the mop material thereto rapidly on one operation.

Claim:

As an article of manufacture, a mop comprising a head, an inverted channeled annulus, mop strands looped over the annulus and retaining means passing through the annulus and into the head for clamping the strands 80 between the annulus and head.

In testimony whereof he affixes his signature.

ALBERT HENRY CROLLY.
